UNITED STATES PATENT OFFICE.

AMOS SHEPARD, OF PLANTSVILLE, AND HOSEA MANN, OF TORRINGTON, CONNECTICUT; SAID SHEPARD ASSIGNOR TO SAID MANN.

SAVINGS-BANK-CALENDAR HOLDER.

No. 895,117.

Specification of Letters Patent.

Patented Aug. 4, 1908.

Application filed August 10, 1907. Serial No. 388,052.

To all whom it may concern:

Be it known that we, AMOS SHEPARD and HOSEA MANN, citizens of the United States, residing, respectively, at Plantsville, in the 5 county of Hartford, and Torrington, in the county of Litchfield, State of Connecticut, have invented certain new and useful Improvements in Savings-Bank-Calendar Holders; of which the following is a specification.

Our invention relates to improvements in savings bank calendar holders, and the main object of our improvement is to provide a holder on the front of the bank of such a 15 character as to receive and hold on the front of the bank only such calendar backs or cards as are cut especially therefor.

Many banking houses, in order to increase their savings deposits, have adopted the 20 system of loaning their depositors portable savings banks which are locked and the key retained by some of the banking house officials. In these banks money is placed from time to time by the parties to whom 25 the banks are loaned and at stated periods of time, or when the banks are full, they are returned to the banking house and the amounts found therein credited to the respective depositors.

In order to keep the name of the banking 30 house before the depositor, an advertising card or calendar may be attached to the bank, but of course each banking house desires to have their own advertisement or 35 their own calendar on their own banks. If a calendar is on the bank and that calendar can only be obtained of a particular banking house, the depositor will naturally make a deposit at the end of the calendar 40 month, or year, and get a new calendar, thereby returning the savings bank for deposits, perhaps more frequently than they otherwise would.

In the accompanying drawing: Figure 1 45 is a front elevation of our bank and holder with a calendar held on the face of the said bank. Fig. 1^a is a portion of a calendar back cut especially for this holder and its guard. Fig. 2 is a central vertical section 50 from side to side of the upper part of the case of our bank, with the coin slot and top removed, and showing the inner or rear side of the front and connected parts. Fig. 3 is an enlarged vertical section on the line 55 x x of Fig. 1 of the upper end of the case and

connected parts except the top plate and parts belonging thereto. Fig. 4 is a front elevation of the upper portion of one of our banks with an attached card and a modified form of holder, the said figure being on the 60 same scale as Figs. 1 and 2. Fig. 5 is a sectional view of the same on the line y y of Fig. 4. Fig. 6 is a portion of a card recessed to fit the said holder.

The bank A in the main may be of any 65 ordinary construction. As shown in Fig. 1, it is provided with a top 6 with a coin chute 7 thereon. It is also provided with a closure plate S at the bottom. Upon the middle front near the top is the guard or guard 70 plate 9, which is of less width than the said front. This plate may also serve as the name plate of the banking house. This plate is secured in any proper manner, as for example by rivets 10, to the front of the case 75 so as to project therefrom the full thickness of the plate. The contour of this plate may be made in any pleasing design but we prefer to make it of some special form. The form shown in Fig. 1 is special enough for our purpose. At the top of this name plate is a 80 holder or holding plate 11 with its lower edge fitted to match the upper edge of the guard plate 9 while its ends which constitute the grasping portion, project laterally on each 85 side of the said guard plate. This holding plate 11 is rigidly secured at the middle of its length to the front end of the short arm of an angle lever 12. The longer arm or main portion of the angle lever 12 is on the 90 inner side of the case or receptacle front, the short arm extending towards the front through the slot 13, Fig. 2, near the top. The angle lever is fulcrumed at its lower end in a perforated lug 14 on the inner side of the 95 case. A spring 15 is secured to the front side of the angle lever with its ends bearing on the front inner wall of the case under tension and with a constant tendency to force the holding plate 11 against the receptacle front with 100 which the said holder coacts. The thickness of the guard plate, that is, the projection of the said plate from the receptacle front is greater than will be the thickness of the calendar back 16, or other card designed to be 105 held in the holder. The lengths of the short arm of the angle lever and the long arm of the said lever are so related to the case, the holder, and the name plate, that the holder plate cannot be pulled forward far enough to bring 110

the rear side of the holder plate, at both ends, quite into the vertical plane of the front of the guard plate. This is because the front edge of the longer arm of the angle lever engages the inner side of the front wall of the case and acts as a stop to prevent the holding plate from being pulled too far forward. It will thus be seen that the holding plate cannot be pulled forward far enough to permit of a card to be pushed up behind the holding plate when that card is in front of the name plate. A notch or recess 17 is cut in the upper end of the calendar back, or card 16, the lower part of which recess is of the same contour as the main portion of the guard plate 9. The upper end of the said recess has rectangular corners as shown in Fig. 1^a and as indicated by broken lines in Fig. 1, and the width of the said recess between these rectangular corners is as great as the extreme width of the name or guard plate 9 at the extreme lower edge of the holding plate 11. It will thus be seen that the upper end of the card or calendar back is cut to fit certain edges of the guard plate while a portion of the card immediately by the side of the said certain edges is adapted to be pressed upon by the holding plate. It will also be seen that the front of the receptacle below the holder and guard serves as a support for the major part of the card or calendar back to rest upon. In addition to the calendar proper 24, the calendar back or card may have any desired printed matter thereon.

In order to place the calendar on the bank within the holder, the upper end of the calendar back is placed just below the lowest part of the holding plate with the two side edges of the recess 17 astride the guard plate 9. Then pulling the spring-actuated holding plate 11 forwardly against its spring, the two upper corners of the recessed back can be slipped up behind the holding plate and between it and the front of the case so that the said corners come under the two ends of the holding plate with the lower part of the recess closely fitting the edge of the guard or name plate, as shown in Fig. 1, so that upon releasing the holding plate to its spring, the card or calendar back will be held on the bank front in the position where it has been thus placed.

In Figs. 4 and 5 a modified form of holder is shown with a somewhat different bank B. A name or guard plate 9^a is secured in like manner to the front of the bank, which plate is in the form of a plain shield. This shield is recessed through its middle portion on the back for a width such as is indicated by the parallel broken lines in Fig. 4 and to a depth fully equal to the thickness of the calendar back or card. The case is also provided with an opening 18, Fig. 5, at the front behind the middle of the plate 9^a and a spring 19 is se-

cured on the inner side of the case which spring projects towards the front through the opening 18. The upper end of this spring is provided with a push button 20, that projects through an opening 21 in the plate 9^a. The calendar back or card 16^a for this holder is provided with recesses 22 at its upper end and a central tongue 23, which recesses and tongue together fit the outer edges of the plate 9^a and the recess in the back of the said plate.

In order to place the calendar or other card on the bank so as to be held thereon by the holder, the spring 19 is pushed back away from the bottom wall of the recess in the back of the plate 9^a by pressing on the push button and then the calendar card or back 16^a is put in place by slipping the central tongue 23 up endwise into the recess in the back of the plate 9^a and in front of the spring 19, until the outer edges of the recesses 22 come closely to the side edges of the plate 9^a and the edges of the central tongue 23 substantially abut against the confronting edges in the tongue recess in the plate 9^a, as shown in Fig. 4, 90 when upon releasing the pressure on the push button the calendar will be held in place by the pressure of the spring 19 on the said tongue. In this construction the spring 19 is the equivalent of the spring-actuated holding plate 11 in the holder first described. The edges of the tongue recess in the guard plate 9^a, as well as the lower and side edges of the said plate, are special edges of the guard for the specially cut edges of the card to abut 100 against. The spring actuated plate is adapted to press upon that portion of the card which is immediately by the side of certain edges of the guard plate. In both constructions the calendar back or card must be cut 105 to fit the particular holder and guard to which it is to be applied and the difference between a pull and a push for opening the holder to receive a portion of the card or calendar back, is considered immaterial. By 110 having the guard plate of less width than the front of the bank and placing it near the middle upper front of the bank, leaves an ample seat for a calendar back on both sides of and below the said guard plate. By the 115 employment of such a holder upon the front of a bank, treasure box, or analogous receptacle, the party owning and loaning the banks has control of the calendars or other advertising matter that may be displayed on 120 the bank. It is true that other cards could be cut to fit the holder, but unless the printing thereon was done with special reference to such cutting, the printed matter on the card would probably be mutilated so that the 125 user would prefer the intended card.

We claim as our invention:—

1. A receptacle and holder comprising a receptacle front, a card holder mounted on the said front near the middle upper part 130

thereof, a guard plate mounted on the said front adjacent to the said card holder, and a card having at its upper end specially cut edges to abut special edges of the said guard 5 when the said card is held by the said holder, while the part below the said holder and guard rests upon the receptacle front.

2. A savings bank and holder comprising a receptacle having a front, a calendar back 10 holder mounted on the said front near the upper end thereof leaving the lower part of the said front as a calendar back support, a guard on the upper part of the said front adjacent to the said holder, and a calendar 15 back having at its upper end specially cut edges to abut against special edges of the said guard when the said card is held by the said holder while the lower part of the calendar back is adapted to rest upon the said 20 front below the said holder and guard.

3. A receptacle and holder comprising a receptacle front, a spring actuated holding plate mounted on the said front adjacent to the said guard plate with its grasping portions extended laterally on opposite sides thereof, and a card recessed at its upper end to fit the lower edge of the said guard plate while the upper corners of the said card immediately by the sides of the said recess are 25 adapted to be held in the grasping portions of the said spring actuated holding plate. 30

4. A savings bank and card holder comprising a receptacle having a front, a guard plate mounted on the said front, and having special edges for the edges of a card to abut 35 against, a spring actuated holding plate mounted on the said front immediately by the side of the said edges of the said guard plate, and a card having its upper end cut to fit the said special edges of the said guard plate while 40 the portion of the said card immediately by the side of the said special edges of the said guard is adapted to be pressed upon by the said holding plate.

5. A receptacle and holder comprising a 45 receptacle front, a guard plate projecting therefrom, a holder plate at one edge of the said guard plate on the said front for coacting therewith, an angle lever to which said holding plate is rigidly secured, the main 50 portion of the said angle lever being within the receptacle and fulcrumed therein, and a spring between the said angle lever and said receptacle front.
